BASE FOR A LAMP

Hans Schroeder, Chicago, Ill., assignor to
Louis Green, Village of Niles, Ill.

Filed Feb. 18, 1963, Ser. No. 73,590

Term of patent 3½ years

(Cl. D48—20)

FIG. 1 is a front elevational view of a base for a lamp embodying my new design; the rear or the part thereof not shown has the same appearance as the illustrated front part thereof; and

FIG. 2 is a top plan view thereof with portions omitted for convenience of illustration.

The dominant features of my design are shown in full lines.

I claim:

The ornamental design for a base for a lamp, as shown and described.
